UNITED STATES PATENT OFFICE

2,442,167

MACHINE FOR CEMENTING SHOE SOLES

William Griffith, South Pasadena, Calif.

Application March 18, 1946, Serial No. 655,091

5 Claims. (Cl. 12—36)

1

This invention relates to improvements in shoe machinery and concerns primarily a device for facilitating the cementing of shoe soles onto uppers.

It is now common practice to attach shoe soles to uppers by applying cement to an upper on a last and to the sole and to cause the sole to adhere to the upper by subjecting the applied sole on the last to great pressure.

One object of the present invention is to provide an improved machine consisting of a walking beam that is pivotally mounted intermediate its ends and which has two boxes located beneath the walking beam on opposite sides of its pivotal mounting adapted to contain a liquid and presenting a flexible upper surface on which the last with its upper and applied sole may be positioned and which has last pressing means for pressing the last firmly against the upper surfaces of the boxes which last pressing means are guided and restricted to vertical movements and to provide means for pneumatically oscillating or rocking of the walking beam.

Still another object of the invention is to provide a machine for cementing shoe soles onto shoes wherein there is a walking beam equipped on opposite ends thereof with last pressing means for pressing the last downwardly against the pressure surface and which is so arranged that while one last is being pressed by the machine the other last pressing means is in released position to enable lasts to be removed and applied while the first last is being pressed.

With the foregoing and other objects in view, which will be made manifest in the following detailed description and specifically pointed out in the appended claims, reference is had to the accompanying drawings for an illustrative embodiment of the invention, wherein:

Figure 1 is a longitudinal vertical section through a portion of the machine embodying the present invention;

Fig. 2 is a top plan view of a machine;

Fig. 3 is an end view in elevation, parts being broken away and shown in section and may be regarded as taken in the direction of the arrow 3 upon Fig. 1.

Referring to the accompanying drawings wherein similar reference characters designate similar parts throughout, the improved machine comprises a suitable table generally indicated at 10 and having a standard 11 thereon which serves to pivotally mount a walking beam 12. To one end of the walking beam links 14 are pivotally secured and these links serve to connect the

2

walking beam to the piston rod 15 of a pneumatic cylinder 16 within which a piston not shown is reciprocable. Air or other fluid pressure is supplied to the ends of the cylinder through a conduit 16a from any suitable control valve such as a foot operated valve to forcibly elevate or lower the piston and to consequently rock the walking beam 12. In the table on opposite sides of the standard 11 and below the walking beam 12 there are boxes 17 and 18 which are adapted to contain a liquid such as water indicated at 19. The boxes have outwardly extending flanges adjacent the top thereof which rest on the table 10 and on these flanges there is positioned a rubber diaphragm 20 preferably covered with a tough but flexible matter such as elk's hide indicated at 21. The rubber diaphragm and its covering 21 are retained on the boxes by means of a clamping ring 22 and cap screws 23. Within the boxes 10 there are wooden heel supports 24 which rest on the bottom surfaces of the boxes and have their tops only slightly spaced below the bottom of the rubber diaphragm 20. These supports carry wooden dowels 25 that extend substantially entirely across the box to maintain the supports 24 in position therein. The supports 24 are adapted to be positioned beneath the heel of the last. At the outer sides of the boxes there may be stops 26 preferably resiliently faced as at 27 such as 30 by leather or the equivalent and the heel of the shoe is adapted to be positioned against such stops.

At approximately equal distances from the pivot 13 links 28 and 29 are pivotally mounted on the walking beam as at 30 and 31 respectively. These links serve to suspend small beams 32 and 33 which have at their outer ends seats 34 and 35 adapted to engage over the heel portion of the last L. The movements of these beams are restricted or guided to vertical movements by means of arms 36 which extend rearwardly and slidably engage vertical guide rods 37 and 38 respectively that are mounted on the back of the table. Collars 39 and 40 are slidable along the links of these beams so as to be adjustable to the lengths of the last. These collars carry toe engaging portions 41 that are preferably resiliently faced such as by leather indicated at 42. These portions are adapted to engage over the toe of the last and cooperate with the portions 34 and 35 in pressing the last and is applied material downwardly against the tops of the boxes with great effort. Springs 43 and 44 may connect the beams 32 and 33 to the links 28 and 29 urging the beams into positions wherein the heel

seats 34 and 35 are engageable with the lasts L in advance of the toe portions 41. Thus although the beams 32 and 33 are pivotally connected to the lower ends of the links to accommodate themselves to the last the movements of the beams 32 and 33 are restricted to vertical movements by the sliding engagement between the arms 36 and the vertical guide rods 37 and 38.

In the use of the machine a last having an upper thereon and having a cemented sole applied thereto is positioned on the upper surface of one of the boxes such as that illustrated in Fig. 1. On supplying the fluid pressure such as compressed air or the equivalent to the pneumatic cylinder 16 the piston rod 15 will be forced upwardly to rock the walking beam 12 about 13 as a center in a counter-clockwise direction. As the last pressing means provided by the beam 32 descends, its heel seat 34 engages the top of the last over the heel and presses the heel downwardly. As the heel usually is of less area than the sole the heel would normally tend to penetrate or press the flexible covering of the box downwardly to a greater extent than the sole. Some downward movement is permissible but is ultimately limited by the engagement of the underside of the rubber diaphragm with the block or support 24. Continued downward movement causes the toe portion 41 to engage over the toe of the last, the beam 32 rocking slightly with respect to the links 28 and against the action of the spring 43 and the toe is subsequently urged into firm engagement with the top surface of the box. In this manner it will be noted that the pressure afforded by the liquid within the box is evenly distributed even though the heel may be considerably narrower than the toe. While the walking beam is in this position a last over the box 18 may be removed and a new last with its applied upper and sole may be installed thereon. The flow of fluid to the pneumatic cylinder 16 is then reversed to rock the walking beam in a clockwise direction about 13 as a center to cause the last that is applied to the box 18 to be pressed downwardly thereagainst in a similar manner and to cause the last pressing means provided by the beam 32 to lift and release the last L on the box 17. When this last is released it may be removed and a new last substituted therefor while the pressure is being continuously applied to the part positioned on the box 18. In this manner, while one shoe is having pressure applied thereto to cement the sole thereon another last may be removed and replaced during this small period of time.

It will be appreciated from the above-described construction that the improved machine is very simple and highly durable and that while one shoe is having its sole cemented in place by the application of great pressure that another shoe may be removed from the machine and a new shoe applied thereto in its place. The stops at 26 and 27 prevent rearward sliding or slipping and as the heel has its downward movement ultimately limited by the block 24 the action is to press the shoe downwardly against the boxes with a small rolling action from heel to toe which is highly advantageous. The boxes merely rest by means of their flanges on top of the table and in the event that it is necessary to remove and replace either or both of the boxes this may be readily accomplished as the boxes need only be lifted out of the apertures in the table that they occupy. Consequently shut-down time

occasioned by the necessity of replacing the boxes is greatly reduced if not entirely eliminated.

Various changes may be made in the details of construction without departing from the spirit and scope of the invention as defined by the appended claims.

I claim:

1. A machine for cementing shoe soles to uppers comprising a walking beam, means for pivotally mounting the walking beam intermediate the ends thereof, a flexible support beneath the walking beam on each side of the pivotal mounting, last pressing means on the walking beam over the supports for pressing a last thereagainst, means for restricting the last pressing means to vertical movements, and means for rocking the walking beam.
2. A machine for cementing shoe soles to uppers comprising a walking beam, means for pivotally mounting the walking beam intermediate the ends thereof, a flexible support beneath the walking beam on each side of the pivotal mounting, last pressing means on the walking beam over the supports for pressing a last thereagainst, means for restricting the last pressing means to vertical movements, and pneumatic means for rocking the walking beam.
3. A machine for cementing shoe soles to uppers comprising a walking beam, means for pivotally mounting the walking beam intermediate the ends thereof, means for rocking the walking beam, links pivotally connected to the one beam on opposite sides of its pivot, last pressing means pivotally mounted upon the links, means on the links for guiding the last pressing means and restricting its movements to vertical movements, and boxes arranged beneath the last pressing means, said boxes being filled with liquid and presenting flexible covers against which the lasts may be positioned.
4. A machine for cementing shoe soles to uppers comprising a walking beam, means for pivotally mounting the walking beam intermediate the ends thereof, means for rocking the walking beam, last pressing means suspended from the walking beam equal distances from and on opposite sides of the pivot, and a support beneath each of the last pressing means against which the last pressing means may press a shoe upper and shoe sole.
5. A machine for cementing shoe soles to uppers comprising a walking beam, means for pivotally mounting the walking beam intermediate the ends thereof, means for rocking the walking beam, last pressing means suspended from the walking beam equal distances from and on opposite sides of the pivot, a support beneath each of the last pressing means against which the last pressing means may press a shoe upper and shoe sole, and means restricting the last pressing means to movements perpendicular to the planes of the supports.
